SPARK PLUG CLEANER

Hector Rabezzana, Flint, Mich., assignor to General Motors Corporation, Detroit, Mich., a corporation of Delaware

Application March 2, 1939, Serial No. 259,307

6 Claims. (Cl. 51—8)

My invention relates to spark plug cleaning devices wherein carbon encrusted oil and like deposits of objectionable material which accumulate upon the spark gap elements, and upon the inner end of the plug which is exposed to high temperature of the burning gases within the combustion chamber of an engine when the plug is in use, and which interfere with the proper action of the plug and may cause failure thereof. 5
10 by short circuiting the spark gap, are removed from the plug by a jet of air and entrained abrasive material and the plug restored to its initial condition as regards its efficiency for the purpose for which it is designed.
15 The objects of my invention are to provide improved valve mechanism for controlling the flow of air under pressure to a nozzle arranged to project a stream of air and abrasive against the spark plug being cleaned, to provide improved
20 means for supporting the plug in proper position so that the jet will act effectively thereupon, to provide improved air filtering means for preventing dust laden air from escaping to the external atmosphere, and to otherwise improve spark plug cleaning devices of the sand blast type to which
25 my invention relates.

With the above and other objects of invention in view, my invention consists in the improved spark plug cleaning device illustrated in the accompanying drawings and hereinafter described and claimed; and in such variations and modifications thereof, within the scope of the concluding claims, as will be obvious to those skilled in the art to which my invention relates.

35 In the drawings accompanying and forming a part of this specification:

Figure 1 is a view showing my improved spark plug cleaner partly in side elevation and partly broken away to show features of internal structure.

Figure 2 is a view showing a section upon a horizontal plane indicated by the line 2—2, Figure 1, looking down.

45 Figure 3 is a fragmentary view in side elevation as seen from a position to the left of Figure 1.

Figure 4 is a view showing a section upon a plane indicated by the line 4—4, Figure 1, looking down.

Figure 5 is a sectional view showing certain features of valve mechanism of my device, upon a plane indicated by the line 5—5, Figure 9, looking toward the left.

55 Figure 6 is a view similar to Figure 5 but show-

ing other valve mechanism features upon a plane indicated by the line 6—6, Figure 9.

Figure 7 is a sectional view showing features of the abrasive material nozzle of my device.

Figure 8 is a fragmentary view showing certain features of my device.

Figure 9 is a view showing a section upon a plane indicated by the line 9—9 of Figures 5 and 6.

Referring now to the drawings wherein the preferred embodiment of my invention is illustrated, the numeral 10 designates an external cylindrical casing made of sheet metal, and 11 designates an abrasive material hopper arranged within and concentric with the casing 10 and 15 having a cone-shaped lower end 12 as shown. This hopper is supported from the upper end of the casing 10 by an inclined annular sheet metal member 13 the periphery of which is flanged, and seamed with the wall of the casing, as shown 20 at 14; or fastened to said wall by welding, by rivets, or otherwise so long as the supporting member is supported within the casing 10 and serves to support the hopper 11 which contains the sand or like abrasive material used to clean 25 the plugs. The flanged periphery of the supporting member 13 extends above the casing 10, as at 15, to thereby receive and provide a seat for the lower end 16 of a cover 17 which closes the upper end of the casing 10 and serves as a 30 support for certain valve mechanism, spark plug supporting means and other mechanism as will hereinafter appear. The cover 17 is shown as fastened to the upwardly extending flange 15 of the annular supporting member 13 by screws 35 18, as many as may be deemed necessary, extending through the lower end of the cover and through said flange.

The supporting member 13 has a series of openings 19 formed, preferably, by striking up 40 small areas of the wall thereof as shown; and the numeral 20 designates a conical deflector having a central opening 21, and an upwardly extending annular flange at its periphery which lies within the flange 15 of the hopper supporting 45 member 13. This deflector is shown as contacting with the struck up portions of the member 13 whereby the holes 19 are provided, and its periphery may or may not be welded or otherwise secured to the flange 15 of the conical supporting 50 member 13.

When the cleaner is in use air, which is supplied to the cleaning nozzle under pressure as will next appear, and sand or equivalent abrasive material which is entrained by the air, are 55

deflected downward and through the opening 21. The heavier particles of the abrasive material are thus returned to the hopper 12 to be used over again; whereas such part thereof as has been 5 reduced to impalpable powder which will be carried onward by the air stream flowing through the cleaner, will be carried forward as dust through the space between the deflector 20 and supporting member 13; and downward through 10 the holes 19 and into the annular space between the external casing 10 and the hopper 11. The dust laden air then flows from the lower end of the casing 10 through an air filter 22 housed within a recess provided for it in the casing 10, 15 and having a mass of fibrous filtering material 23 which arrests and retains the dust carried by the air stream; and through an opening 24 in the filter 22 and into the external atmosphere.

The numeral 25 designates a nozzle which is 20 supported from the top wall of the cover 17 as by a stirrup 26, and whereby a stream of air and sand or like abrasive material is discharged against the lower end of a spark plug to be cleaned. This nozzle comprises a hollow casing 27, a concentrically disposed jet 28 to which air under pressure is supplied through a pipe 29, an abrasive material supply tube 30 depending into the hopper 12, and through which abrasive material is supplied to the interior of the casing 27, 30 and a vacuum relieving conduit 31 whereby the interior of the casing 27 may be placed in communication with the external atmosphere.

The supply of air under pressure through the 25 pipe 29, and also the flow of air from the atmosphere through the vacuum relieving conduit 31, are controlled by two valves within a valve casing 32 which is secured to and carried by the head 17 and located to one side and beyond the periphery thereof, as shown; one valve 33 when 40 off its seat 34 serving to admit air under pressure from a source 35 to the supply pipe 29, and the other valve 36 when in its upper position serving to place the conduit 31 in communication with the atmosphere through a slot 37 in the 45 casing 32 and when in its lower position against its seat 38 to interrupt communication with the atmosphere.

The valves 33 and 36 are carried by stems 39, 50 the first of which projects above the casing 32 further than the second, and the stems and valves are forced upward by springs 41, 42 within the casing 32 as shown.

The valves 33 and 36 are both operated by a 55 tappet 43 carried by a lever 44 which is pivotally supported at 45 by arms 46 extending from the valve casing 32; and which lever has a hood 47 at its free end and located above the spark plug being cleaned to prevent possible diffusion of the abrasive material being used into the surrounding atmosphere. The lever 44 has a stop 48 which engages the casing 32 to limit upward swinging movement thereof; and the lever is shown as bifurcated, and the tappet 43 as a roller supported by a pin 49 extending between the 60 two parts thereof.

In using my improved spark plug cleaner the lower threaded end of a spark plug to be cleaned is inserted in an opening in a rotatable support 50, as shown, and the hood 47 is depressed by the 70 hand of the operator thus swinging the lever 44 upon its pivotal support 45.

The first effect of this movement is to open the valve 33 as the tappet 43 engages the longer stem 39 of this valve, but not to depress the valve 36 75 as the tappet has not yet engaged the shorter

stem 40 of this valve. The operator may pause with the parts in this position, with the valve 33 opened and the valve 36 in its uppermost position; during which time air under pressure will flow through the pipe 29 and the nozzle 28, but 5 abrasive material will not be drawn from the hopper 12 because the interior of the casing 27 is in communication with the atmosphere through the vacuum relieving conduit 31 and the slot 37.

Air only and unmixed with abrasive material will be blown against the spark plug so long as the valve 33 is off its seat, and the valve 36 is out of contact with its seat 38. When, however, the hood 47 is further depressed the valve 33 15 will be completely opened and the valve 36 will be pressed against its seat 38; which action will interrupt communication between the casing 27 and the atmosphere through the conduit 31 and slot 37, and mingled air and abrasive material 20 will be projected against the plug being cleaned.

The support 50 should be rotated during the cleaning operation so that the jet of air and abrasive material engage the plug throughout its entire circumference. After the plug has been 25 cleaned the operator will permit the hood 47 to rise under the influence of the springs 41, 42. He may, however, pause with the valve 36 in its uppermost position but while the valve 33 is still partially open, and during this interval a stream 30 of air will flow against the plug to blow residual dust therefrom; but no abrasive will flow with the air stream because the interior of the nozzle casing 27 will be in communication with the atmosphere through the vacuum relieving conduit 35 31 and the slot 37.

The plug supporting member 50 may be made of molded rubber or equivalent material, and the upper end thereof is shown as having a metallic lining sleeve 51 molded in place and adapted to receive the threaded lower end of a spark plug as shown; and the lower end of this supporting member has a circular guide 52 which fits closely within an internal circular seat at the upper end of a bearing member 53 which is 45 carried by the top wall of the cover 17; the plug supporting member 50 being rotatable within the bearing member 53 as hereinbefore explained, and the plug supporting member 50 having a peripheral flange 54 for limiting downward movement thereof.

The bearing member 53 has two internal circular bearing seats arranged one above the other, and eccentric with one another; from which it follows that if a plug supporting member like 55 the member 50 except that its lower end is of such diameter as to fit closely within the smaller lower end of the bearing member 53, be used in place of the plug supporting member 50 shown, the axis about which the substituted plug supporting member will rotate will be shifted to the left; thus shifting the plug being cleaned to the left relative to the jet discharged from the nozzle 25 and enabling the device to be used for cleaning plugs of smaller diameter than the particular plug contemplated in the foregoing description.

Having thus described and explained my invention, I claim and desire to secure by Letters Patent:

1. In a spark plug cleaning device of the class described, means for supporting a spark plug to be cleaned; an aspirating nozzle arranged to discharge a stream of air and abrasive material against said spark plug; means supplying abra- 75

sive to said nozzle; a pipe leading to said nozzle for supplying air under pressure thereto; a normally closed valve for controlling the flow of air through said pipe; a vacuum relieving conduit leading from said nozzle to the atmosphere; a normally open valve for controlling said conduit; a manually operable hood arranged above said plug supporting means; and means operable by said hood and through which movement imparted to said hood is communicated to said valves.

2. In a spark plug cleaning device of the class described, means for supporting a spark plug to be cleaned; a nozzle arranged to discharge a stream of air and abrasive material against said spark plug; a pipe leading to said nozzle for supplying air under pressure thereto; a normally closed valve for controlling the flow of air through said pipe; a vacuum relieving conduit leading from said nozzle to the atmosphere; a normally open valve for controlling said conduit; an oscillating lever associated with both said valves; and a manually operable hood at the free end of said lever and disposed above said spark plug supporting means.

3. In a spark plug cleaning device of the class described, a nozzle arranged to discharge a jet of air and abrasive material against the lower end of a spark plug to be cleaned; a rotatable spark plug supporting member; and a bearing member for supporting said plug supporting member; said bearing member having two internal circular bearing seats arranged one above the other, and which seats are eccentric relative to one another.

4. In a spark plug cleaning device of the class described and in combination with a casing having an open upper end, and an abrasive material hopper inside said casing; a cover for closing the upper end of said casing; a supporting member carried by said cover for supporting a plug to be cleaned; a nozzle supported by said cover and located beneath the same, and so arranged as to discharge a jet of air and abrasive material against the lower end of a spark plug supported by said supporting member; a valve casing carried by said cover; two valves within said valve casing one adapted to control the flow of air under pressure to said nozzle, and the other to control a communication between said nozzle and the atmosphere; an oscillating lever pivotally sup-

ported upon said valve casing, and which lever is operatively associated with both said valves; and an abrasive material supply tube leading from said hopper to said nozzle.

5. In a spark plug cleaning device of the class described and in combination with a casing having an open upper end, and an abrasive material hopper inside said casing; a cover for closing the upper end of said casing; a supporting member carried by said cover for supporting a plug to be cleaned; a nozzle supported by said cover and located beneath the same, and so arranged as to discharge a jet of air and abrasive material against the lower end of a spark plug supported by said supporting member; a valve casing carried by said cover and located to one side of and beyond the periphery thereof; two reciprocating valves within said valve casing; a pipe leading from said valve casing to said nozzle for supplying air under pressure thereto; a vacuum relieving conduit leading from said nozzle to said valve casing and to the atmosphere; an oscillating lever supported by said valve casing and adapted to operate both said valves; and an abrasive material supply tube leading from said hopper to said nozzle.

6. In a spark plug cleaning device of the class described and in combination with a sheet metal casing having an open upper end, and an abrasive material hopper within and smaller than said casing so as to provide an annular space between the two; an inclined supporting member within the upper end of said casing for supporting said hopper, and which member has a series of openings arranged above the space between said casing and said hopper; a conical deflector arranged above and spaced from said supporting member, and having a central opening disposed above said hopper; an air filter housed in a recess provided within said casing, and through which dust laden air flows from the annular space aforesaid to the atmosphere; a cover for closing the open upper end of said casing; means carried by said cover for supporting a spark plug to be cleaned; a nozzle for directing a jet of air and entrained abrasive material against said spark plug; and means for supplying air under pressure to said nozzle.

HECTOR RABEZZANA.
